CASSEROLE

Willis A. Stageberg, Minneapolis, Minn., assignor, by
mesne assignments, to Plastics, Inc., St. Paul, Minn., a
corporation of Delaware

Filed Aug. 2, 1967, Ser. No. 8,096

Term of patent 14 years

Int. Cl. D7—01

U.S. Cl. D44—15

FIG. 1

FIG. 2

FIG. 3

FIG. 4

FIG. 5

FIGURE 1 is a top plan view of a casserole showing my new design;

FIGURE 2 is a right side elevational view;

FIGURE 3 is a front elevational view;

FIGURE 4 is a bottom plan view of the cover member;

FIGURE 5 is an enlarged fragmentary sectional view on the line 5—5 of FIGURE 1; and

FIGURE 6 is an enlarged fragmentary elevational view of the cover member.

The essential features of my design reside in the cover member having the specific configuration shown.

I claim:

The ornamental design for a casserole, as shown and described.
